Attorney

UNITED STATES PATENT OFFICE.

JOSIAH P. WORTHINGTON, OF STEAMBOAT SPRINGS, COLORADO.

DESIGN FOR A WRENCH.

50,372.

Specification for Design.

Patented Feb. 20, 1917.

Application filed March 10, 1915. Serial No. 13,544. Term of patent 14 years.

To all whom it may concern:

Be it known that I, JOSIAH P. WORTHINGTON, a citizen of the United States, residing at Steamboat Springs, in the county of Routt and State of Colorado, have invented a new, original, and ornamental Design for a Wrench, of which the following is a specification, reference being had to the accompanying drawing, forming part thereof.

Figure 1 is a perspective view of a wrench, showing my new design, and

Fig. 2 is a similar view looking at the opposite side of the wrench.

I claim:

The ornamental design for a wrench, as shown.

JOSIAH P. WORTHINGTON.

Witnesses:

MATTIE WORTHINGTON,
A. H. POPPEN.
